UNITED STATES PATENT OFFICE.

GEORGE G. FRYER, OF SYRACUSE, NEW YORK.

METAL BARREL.

1,080,825.

Specification of Letters Patent.

Patented Dec. 9, 1913.

Application filed January 3, 1912. Serial No. 669,248.

To all whom it may concern:

Be it known that I, GEORGE G. FRYER, a citizen of the United States, residing at Syracuse, in the county of Onondaga and State of New York, have invented certain new and useful Improvements in Metal Barrels, of which the following is a specification.

Such barrels have heretofore been made of sheet steel, the barrel body being in the form of a cylinder and in a single piece. Such barrels are difficult to handle because of their cylindrical shape which prevents their being readily directed when rolled from place to place. Moreover since they are made in a single piece they occupy the same space when empty as when full, and hence cannot be conveniently returned for re-use but are usually destroyed when emptied.

The object of my invention is to provide a sheet metal barrel which, while being as convenient and suitable for the uses to which such barrels are generally applied as those heretofore made, shall be free from the above stated defects. To this end I, in the first instance, make the barrel body in two parts, each of which preferably forms one half of the barrel, which are joined together on its central circumference to make the completed barrel body. By reason of this manner of construction the two halves of the barrel may be spun out so that the completed barrel shall be of a bilged shape instead of being in the form of a cylindrical drum as heretofore. I also provide means for securing the two parts of the barrel body together to make a complete container and such means may, as in the preferred form hereinafter described, present a narrow bearing surface upon which the barrel may be easily turned when rolled from place to place even though it be made in the form of a cylinder.

My invention will be best understood by reference to the accompanying drawings illustrating an embodiment thereof. Figure 1 of which shows an elevation of a barrel body with its two parts joined together by a connecting band, which is shown as partly broken away. Fig. 2 shows a section of a part of the shell of the barrel and the connecting band on the line 2-2 Fig. 1; Fig. 3 shows a portion of the two halves of the barrel body with the connecting band ready to be put in place; Fig. 4 is a plan view of a portion of the barrel body on its central cir-

cumference, showing the two halves joined together; Fig. 5 is an elevation showing a portion of a circumferential band with connecting lugs thereon; Figs. 6 and 7 show corresponding parts of the two halves of the barrel body with lugs thereon adapted to engage with corresponding lugs on the circumferential band; Fig. 8 is an elevation of parts of the two halves of the barrel showing in detail a modified means of attaching lugs thereto.

Referring to the drawings, A, A', indicate the two halves of a barrel body. Each of these is provided with a head, B, forming the usual barrel heads, and is of such size and shape that when the open ends of the two parts are placed together they will form a complete barrel body with a central circumferential division. The parts, A, A', are made of sheet metal and are preferably spun out in the process of manufacturing, or otherwise treated in a manner that will be well understood by those skilled in the art, so that they are larger at their open ends than at their closed ends, and thus the barrel body formed by putting them together is of a bilged shape, i. e., larger on its central circumference than at its ends.

Each of the parts, A, A', is provided along its edge with a series of lugs or projections, a, a', so shaped that when they are put together in pairs as shown in Figs. 1 and 3, they form a series of wedge shaped lugs or projections around the central circumference of the barrel.

C. indicates a metal band arranged to surround the barrel on its central circumference and provided interiorly with projecting lugs c, c', arranged in pairs. The lugs, c, c', of each pair are so spaced apart as to provide between them a space into which a pair of the lugs, a, a', on the barrel body may be driven and closely fitted.

In assembling the two parts, A, A', to form a barrel body their open ends are placed together edge to edge, so that the lugs a, a', are assembled in pairs. The band C, is then put in place around the center of the barrel, the space between each pair of lugs, c, c', being opposite a corresponding pair of the lugs, a, a', and the band C is then turned so that the lugs, a, a', enter and are closely held between the lugs, c, c'. In this manner the two halves of the barrel are closely drawn and locked together, and thus held from separation. The accidental turning of

the band, C, in the opposite direction with consequent separation of the parts, A, A', may be prevented by the insertion of any suitable wedge as a piece of strap iron, D, 5 inside the band, C, and between the interlocked lugs on the band and the barrel. When the barrel is emptied the parts, A, A', may be separated by turning the band, C, so as to disconnect the lugs. The barrel 10 halves, A, A', may then, by reason of their bilged shape, be nested for shipment, and thus conveniently and economically returned for refilling. The circumferential locking band also provides a narrow bearing upon 15 which the barrel can easily be turned in rolling it from place to place.

In Fig. 8, which shows a part of each half of the barrel at its central circumference, I have illustrated a modified and preferred 20 means of attaching the lugs a, a', to the barrel. In this case the lugs, a, a', are attached to rolled steel bands, A², A³, which are attached to the two halves of the barrel, as by riveting, adjacent the central circumfer- 25 tial seam. These bands can be rolled out in lengths and then cut and welded together to form the bands and the lugs can be struck up in the process of rolling or spot welded to the bands as may be desired.

30 It will be understood that the means for securing the parts of the barrel together may be largely modified in ways that will readily occur to those skilled in the art, without departing from the spirit of my invention which is not limited to the exact form 35 of locking device illustrated in the drawings.

What I claim as new and desire to secure by Letters Patent is:—

1. The combination with a metal barrel, 40 formed in separated halves, of a band secured to each half adjacent the central circumference of the barrel, lugs on said bands arranged to be joined in pairs when the barrel sections are together and a circumferen-

tial band provided with separated lugs be- 45 tween which the said first mentioned lugs are adapted to engage.

2. As a means of joining together the parts of a metal barrel made in separable sections a series of lugs secured to the two sections of the barrel adjacent their joining edges and arranged to be joined in pairs to form wedge-shaped members when the barrel sections are together and a circumferential band rotatable upon the barrel and provided with separated lugs between which the first mentioned pairs of lugs are adapted to be engaged by the rotation of the band. 55

3. In a metal barrel made in separable sections, the combination of a series of lugs 60 secured to the two sections of the barrel adjacent their joining edges and arranged to be joined in pairs when the barrel sections are together, a circumferential band provided with separated lugs between which the first mentioned pairs of lugs are adapted 65 to be engaged by a rotary movement of the band and means for preventing the rotation of the band on the barrel when the sections thereof are engaged. 70

4. In a metal barrel composed of separable sections the combination of a circumferential band adapted to surround the exterior of the barrel on the line of separation between the sections and having on its interior surface lugs arranged to provide V shaped slots, and lugs secured to the two sections of the barrel adjacent their joining edges and arranged to engage in said slots when the barrel sections are together. 75

In testimony whereof, I have hereunto subscribed my name, this 26th day of December A. D., 1911.

GEORGE G. FRYER.
